UNITED STATES PATENT OFFICE.

GEORGE W. KAFER, OF TRENTON, NEW JERSEY.

ICE-SUPPORT AND WATER-COOLER.

1,237,050.

Specification of Letters Patent.

Patented Aug. 14, 1917.

Application filed November 15, 1916. Serial No. 131,477.

To all whom it may concern:

Be it known that I, GEORGE W. KAFER, a citizen of the United States, residing at Trenton, in the county of Mercer and State 5 of New Jersey, have invented certain new and useful Improvements in Ice-Supports and Water-Coolers, of which the following is a specification, reference being had to the accompanying drawings.

10 This invention relates to refrigerators and more particularly to a combined ice support and drinking water cooler for use in refrigerators.

One object of this invention is to provide 15 an ice support to be used in refrigerators having therein a water passage and provide improved means whereby the water passage may be connected to water inlet and outlet pipes.

20 A further object is to improve the details of construction of devices of this character so as to render them easy of application in a refrigerator and cheapen the cost of construction and render them thoroughly effective in use.

Other objects will appear in the course of the following description.

My invention is illustrated in the accompanying drawings, wherein—

30 Figure 1 is a side elevation of my ice support partly in section, the refrigerator being shown in dotted lines;

Fig. 2 is a top plan view of the support;

Fig. 3 is a top plan view of the lower 35 section of the support;

Fig. 4 is a perspective view of the pipe section 23;

Fig. 5 is a sectional view on the line 5—5 of Fig. 2; and

40 Fig. 6 is a fragmentary sectional view on the line 6—6 of Fig. 5.

Referring to the drawings it will be seen that this ice support consists of a preferably 45 rectangular body designated 10 which is made of porcelain, enamelware, or any other suitable sanitary material, the under face of the body 10 being flat and the upper face 11 being parallel to the under face and provided with longitudinally extending ribs 50 12 for the support of ice. The front of the body 10 is formed upon its upper face with a slightly raised wall 13 with which the ribs 12 intersect. The rear end of the body is formed with a relatively high wall 14 and 55 the sides with the walls 15 which at their rear ends are level with the wall 14 and at

their forward ends are level with the wall 13. The rear end of the body is also formed with the drainage opening 16 disposed at the middle of the body and from which extends the drain pipe 17, this drain pipe being removable but being held in place by the screw threaded nut 18 whereby the flared mouth of the body may be drawn down into tight engagement with the wall 60 of the drainage opening 16.

The body 10 is formed with a water cooling passage 19. This passage extends laterally back and forth across the body 10 and at one end extends forward as at 20 and 70 at its rear end extends laterally as at 21. An inlet pipe 22 operatively connects with the inlet end 21 of the passage while an outlet pipe 23 operatively connects with the outlet end 20 of this passage. Preferably 75 both the side and end wall through which the water passage connects with the pipes 22 and 23 are formed with seats for the inner ends of the pipes 22 and 23 respectively. Each of these pipes, as illustrated in Fig. 4, 80 is provided at its inner end with the laterally projecting lugs 24 and the wall through which the terminal end 20 or terminal end 21 of the passage 19 extends is formed with the outwardly projecting boss 85 25 and with an annular recess 26 adapted to receive the lugs 24. The wall of the passage 20 or 21 is also longitudinally slotted at diametrically opposite points as at 27 for the insertion of the lugs 24 so that the pipe 90 22 or 23 may be inserted with the lugs in the slots 27, pushed inward to its full extent, and then turned a quarter turn so that the lugs will engage in the recess 26. A clamp nut 28 is then applied to the pipe 22 95 or 23 and turned up so as to clamp the pipe securely to the body 10. The pipe sections 22 or 23 are provided with standard gage threads and of course will be of a length to suit the refrigerator with which 100 the device is used. Preferably the pipe section 23 is connected to a tap 29 for controlling the outflow of water. Preferably the pipe section 22 is connected to a source of supply, as for instance to the regular house 105 mains.

In the use of this invention the body 10 is set on such an incline that the upper edges of the walls 15 are horizontal. Under these circumstances the upper face 11 of the body 110 will be downwardly and rearwardly inclined and the plane of the convoluted passage 19

will be at an inclination to the horizontal so that the outlet end of this passage will be above the inlet end thereof. This ice support may be mounted within the refrigerator 5 in any suitable manner and may be either built into the refrigerator initially or afterward added to the refrigerator after its completion. In order that the passage 19 may be formed within the body 10, the body is preferably made in two sections, afterward connected in any suitable manner so as to be watertight. The walls of the passage 19 are thoroughly glazed and the entire surface of the body 10 is thoroughly glazed. It will be 10 seen that the body 10 by supporting the ice will become thoroughly cooled and that the water which may be contained within the passage or may pass through the passage 19 will be thoroughly cool without coming in 15 contact with the ice and being contaminated thereby. Furthermore it will be seen that no odors or effluvia of any kind can have access to the water in the passage 19 and contaminate the same. By placing the body 10 so 20 that the plane of the passage is inclined downward and rearward, the ice placed upon the support will slide back to the rear end thereof as it is used and the water from the ice will naturally run off to the drainage 25 opening. Furthermore by so placing the body, the passage may be emptied of water in cold weather. This is accomplished by disconnecting the passage from the source 30 of water and allowing the water to drain out through the passage, thus overcoming all danger of freezing. In order to clean the device it is only necessary to disconnect the water pressure and fill the passage from the tap or spigot 29 with water and soda and 35 allow this to stand some time and then connect the coil with the city pressure and wash out.

While I have heretofore referred to this device as being used for ordinary refrigerators for the purpose of cooling drinking water, I wish it understood that the device 40

may be applied also in caf s for cooling beer or other beverages.

Having described my invention, what I claim is:

1. In an ice support and water cooler of the character described, a body for supporting ice and having a water passage therein, the exterior of the body having a boss and a water passage extending out through said boss, the water passage at its end being formed with oppositely disposed slots and with an annular recess into which said slots extend, a pipe disposed in the water passage having oppositely disposed lugs engaged in 55 said recess and adapted to be shifted through the slots, and a nut on the pipe engaging the face of the body and drawing the lugs into 60 firm engagement with the annular recess.

2. In an ice support and water cooler of the character described, a body for supporting ice and having a convoluted liquid passage formed therein, the exterior of the body having a boss and a water passage extending out through said boss, the water passage at 65 its end being formed with longitudinally extending slots and with an annular recess into which the slots extend, and a pipe in the water passage having lugs engaged in said 70 recess and adapted to be shifted through the slots, a nut on the pipe engaging the face of the body and drawing the lugs into firm engagement with the recess, the upper face of 75 said body being formed with an upwardly flaring recess and a drainage opening leading downward from said recess, and a drain pipe disposed through said opening and having 80 a head at its upper end engaging in the flared portion of the recess, and a nut on the pipe holding the pipe in place within 85 the drainage opening.

In testimony whereof I hereunto affix my signature in the presence of two witnesses.

GEO. W. KAFER.
